UNITED STATES PATENT OFFICE.

GUSTAVE HUMBER, OF DENVER, COLORADO.

ARC-LIGHT.

1,146,498.

Specification of Letters Patent. Patented July 13, 1915.

Application filed May 6, 1914. Serial No. 836,636.

To all whom it may concern:

Be it known that I, GUSTAVE HUMBER, a citizen of the United States, residing at Denver, county of Denver, and State of Colorado, have invented certain new and useful Arc-Lights, of which the following is a specification.

This invention relates to certain new and useful improvements in arc lamps, and has for its primary object to provide means whereby a steady light may be maintained without the use of manual interference for feeding the carbons as they become burned.

A further object of the invention is to provide means for initially establishing the arc between normally contacted electrodes and for automatically maintaining the same.

A still further object of my invention is to provide in connection with an arc lamp, improved means for supporting and feeding the carbons, in order that the same may be fed or adjusted automatically to maintain the requisite gap between their points to produce a steady and unflickering light.

A still further object of my invention is to provide in an arc lamp provided with a reflector, improved means for adjusting the electrode points with relation to the reflector, whereby the light may be accurately centered to acquire the highest efficiency of the lamp.

With these objects in view, together with others which will appear as the description proceeds, my invention consists in the novel combination and arrangement of parts, all as will be fully described hereinafter, and more particularly pointed out in the appended claims.

My invention will be more readily understood with reference to the accompanying drawings, wherein I have illustrated a practical embodiment of the invention, and in which;

Figure 1 is an elevation, parts broken away, of an arc lamp of the character described to which is applied the improved means for accomplishing the desired ends. Fig. 2 is a sectional view taken upon the line 2—2 of Fig. 1, and looking in the direction indicated by the arrows, Fig. 3 is a vertical section through the reflector of the lamp and illustrating in elevation one of the carbon supporting brackets, Fig. 4 is a detail elevation of the carbon supporting brackets illustrating a slightly modified form of the invention, and, Fig. 5 is a view

similar to Fig. 4, in which there is illustrated a still further modification.

Referring now more particularly to the drawings, 6 and 7 represent respectively the electrodes employed in the usual arc light of this character, and inasmuch as this device is adapted more particularly to be used in connection with head lights for locomotives and other vehicles, a reflector 8 is provided. The electrodes are so arranged as to normally contact at their ends adjacent the center of the reflector, and to this end a pair of brackets 9 and 10 are employed for supporting the same. The bracket 9 is arranged upon the arm 11, which may be formed separately from the main support and secured thereto by the securing elements 12. As shown in Figs. 1 and 2, I have illustrated the bracket 9 secured to the free end of a member 13 forming a part of the standard 14 for supporting the carbons and the component elements of the device. Pivoted as at 15 to the member 13 adjacent the free end thereof, is an arm 16, provided at its outer end with the bracket 10 for the accommodation of the electrode 7. The brackets 9 and 10 are provided with electrode supporting means comprising generally a plurality of alined collars 18, each being of a trifle greater interior diameter than the diameters of the electrodes, in order that the latter may be free to move longitudinally therein, and means hereafter described for holding the electrodes in position therein. The brackets are so arranged with respect to their supporting arms as to converge the electrodes 6 and 7 carried thereby to meet at their projecting ends adjacent the reflector 8. From this arrangement it is obvious that the electrodes are free to gravitate within their respective brackets, and as the arc becomes greater, due to the burning away of the electrode points, the electrodes will automatically feed downwardly by gravitation to again meet adjacent the reflector. It is obvious also that by reason of the arm 16 being pivoted, the same may be swung toward or away from the fixed bracket upon the arm 11 in order to establish the essential arc. To facilitate the ready removal of the arm 11 from the end of the member 13, and in order that the same may be insulated therefrom, the ends of the arm 11 and the member 13 are spliced, as shown in Fig. 2, and insulating material 19 is inserted between the adjacent ends.

For the purpose of automatically establishing and maintaining the arc it is necessary that the pivoted arm 16 be moved toward or away from the stationary arm 11 to 5 properly space the ends of the electrodes contained therein, and to accomplish this, a cam 20 is pivoted upon the member 13 adjacent to and adapted to engage the pivoted arm 15. A rocker arm 21 is secured to the 10 said cam, and is connected at its free end by a link 22 to the adjacent end of a lever 23 pivoted as at 24 upon the member 13. A solenoid 25 is secured adjacent the opposite end of the lever 23, having the core 26 15 thereof in connection with the said opposite end of the lever by the hook member 27. A plate 28 of insulated material is interposed between the hook member 27 and the lever 23 to prevent a short circuit of the 20 electrical current. Between the opposite end of the lever 23 and a stationary support 29 is interposed a retractile spring 30, provided at its extreme end with a wing nut 31 in order that the tension of the same may be 25 regulated. It is obvious from this arrangement that upon rotary movement of the cam 20 the arm 16 carrying the electrode 7 will be moved toward or away from the stationary arm 11 accordingly as the cam is rotated, and it is apparent that the arc at the 30 ends of the carbons is controlled by the flow of current through the solenoid 25. Binding posts 32 and 33 are located upon the arms 11 and 16, to which wires 34 conducting 35 electrical current may be secured, the solenoid 25 being in series with the electrodes.

The clutch device 35 is arranged between the converging carbons to regulate the gravitation of the latter and this clutch device 40 comprises generally a pair of rings 36, one encircling each of the carbons 6 and 7, and being of substantially greater diameter than the latter. A contractile spring 37 is connected at its opposite end to the said rings, 45 and insulated material 38 is positioned in the length of the spring. The rings 36 forming the clutch members rest normally upon the opposite collars forming brackets for the electrodes, and it is obvious that 50 when the arm 16 is swung to its innermost position, the tension of the spring 37 will be relieved as will also the binding action of the rings 36 upon the sides of the electrodes, and the latter will be permitted to gravitate 55 to meet at their points. It will be apparent that upon outward movement of the arm 16 the rings 36, by reason of the tension of the spring 37, will exert inward pressure upon the electrodes to cause a binding action between the sides of the latter and the interior 60 walls of the electrode supporting brackets and in consequence the said electrodes are securely held against gravitation. It is 65 obvious that when the arm 16 is swung to its innermost position, and the points of

the convergent electrodes are engaged, the introduction of electrical current to the electrodes will energize the solenoid 25, causing the latter to attract the core 26, rocking the adjacent end of the lever 23 downwardly, 70 and ultimately rotating the cam 20 to move the arm 16 outwardly to form the gap between the electrode points as illustrated in Fig. 1. As the electrodes burn away at their points and the gap is increased the 75 resistance at the gap is obviously increased, and the strength of the current is reduced to such extent as to weaken the attractive force of the solenoid 25, permitting the spring 30 to rock the inner end of the lever 80 23 downwardly, and ultimately rotating the cam 20 to permit the arm 16 to swing inwardly, whereby the carbons are permitted, by release of the clutch, to gravitate to again meet. In this manner it is obvious 85 that an apparently steady light is maintained without manual interference as long as the carbons last, and the only necessity for manual interference is to replace burned out carbons and to occasionally clean and 90 oil the several movable parts.

In order that the electrode points may be adjusted to be properly centered with relation to the reflector the base 39 of the support is provided with a threaded stem 95 40 upon which is mounted the interiorly threaded sleeve 41, swiveled upon the lower end of the standard 14. Obviously by turning the sleeve 41, vertical adjustment of the standard and the mechanism carried thereby is had.

In Fig. 4 of the drawings I have illustrated a slightly modified form of the device, wherein the brackets supporting the carbons are both secured upon pivoted arms 105 42 and 43, a double cam 44 being provided to operate the said arms to swing inwardly and outwardly. By this arrangement a more even feed of the electrodes may be had, and also a more complete and instantaneous 110 operation of the electrode clutching device.

Fig. 5 illustrates a still further modified form of the invention, wherein the clutch mechanism employed in the above described 115 forms of the invention is dispensed with. The mechanism for clutching the electrodes here used, comprises a pair of cams 45 and 46 pivoted upon the arms upon which the converging electrodes are positioned, and 120 these cams are so positioned as to engage, when in one position, the sides of the electrodes to hold the same securely against movement within the brackets. The cams are provided with arms 47, in pivotal connection with a plate 48, which in turn is connected with the arm 23 by a resilient member 49. In this manner the electrode engaging cams are in direct connection with the solenoid, and the movement or feed- 125 130

ing of the electrodes is not dependent upon movement of the arm or arms supporting the carbons as is the case in the above described forms of the invention.

5 I claim—

1. In an arc lamp, a support, an electrode bracket fixed to said support a second electrode bracket pivoted upon said support, and both of said brackets being provided 10 with means for supporting electrodes in downwardly converging positions, and electrodes arranged in said supporting means to gravitate to meet at their ends coöperating means upon said electrodes for holding the same in position when said brackets are separated, a cam coöperating with said pivoted bracket for swinging the same toward or away from said fixed bracket, a solenoid, and means connecting said cam and said 20 solenoid whereby movement of said cam will be governed by the flow of electric current through said solenoid, substantially as described.

2. In an arc lamp, a support, an electrode bracket fixed to said support, an arm pivoted to said support and provided with an electrode bracket and both of said brackets being provided with means for supporting electrodes in downwardly converging 25 position, electrodes loosely mounted in said supporting means to gravitate therein to meet at their ends, clutches on said electrodes and a spring connecting said clutches normally holding said electrodes in fixed 30 position when said brackets are separated, and means for swinging said arm toward or away from said fixed bracket, substantially as described.

3. In an arc lamp, a support, an electrode bracket fixed to said support, an arm pivoted to said support and provided with an electrode bracket and both of said brackets being provided with means for supporting electrodes in downwardly converging 40 position, electrodes loosely mounted in said supporting means and adapted to gravitate therein to meet at their ends, clutch members on said electrodes, a spring connecting said clutch members whereby said electrodes, are held against gravitation when said arm is swung away from said fixed bracket and will be released upon inward movement of said arm sufficient to relieve the tension of the spring, and means for 45 moving said arm toward or away from said bracket, substantially as described.

4. In an arc lamp, a bracket, an electrode bracket fixed to said support, an arm pivoted to said support and provided with an 50 electrode bracket and both of said brackets being provided with means for supporting electrodes in downwardly converging position, electrodes loosely mounted in said supporting means and adapted to gravitate 55 therein to meet at their ends, means for

holding said electrodes in said brackets, when said arm is rocked away from said fixed bracket, a cam on said support co-operating with said arm to control the movements thereof, a solenoid and core, and a 70 connection between the said core and said cam whereby the movements of the latter are controlled by the movements of the core, substantially as described.

5. In an arc lamp, a support, a pair of 75 arms pivotally secured at one end to said support and adapted to swing toward or away from each other at their free ends, brackets on said arms adapted to hold electrodes in downwardly converging position, 80 electrodes loosely mounted for gravitation in said brackets extending beyond said free ends to meet, clutch members on said electrodes, a spring connecting said clutch members whereby said electrodes are held 85 against gravitation when said brackets are swung apart and will be released upon inward movement of said brackets to allow said electrodes to gravitate, and means governed by the flow of electrical current 90 through said electrodes for controlling the movement of said brackets, substantially as described.

6. In an arc lamp, a support, a pair of 95 arms each pivotally secured at one end to said support to permit of their opposite ends swinging toward or away from each other, an electrode supporting bracket on each of said arms adapted to hold electrodes in downwardly converging position, electrodes loosely 100 mounted for gravitation in said brackets, and extending beyond said free ends to contact at their points, coöperating means for holding said electrode against gravitation in said brackets when said arms are 105 swung away from each other, a cam on said support adapted to engage said arms to swing the same toward or away from each other, a solenoid and core, and a connection between said cam and said core whereby 110 the former will be controlled by movements of the latter, substantially as described.

7. In an arc lamp, a support, an electrode bracket fixed to said support, an arm pivoted to said support and provided with an 115 electrode bracket and adapted to swing toward or away from said fixed bracket, electrodes mounted for gravitation within said bracket and adapted to meet at their ends, means for releasably supporting said electrodes within said brackets, a cam mounted 120 upon said support and adapted to engage said pivoted arm, a lever on said cam, a solenoid, and a link connecting said lever and the core of said solenoid whereby said arm will be rocked when said solenoid is energized, substantially as described.

8. In an arc lamp, a support, an electrode bracket fixed to said support, a second electrode bracket pivoted upon said support, 130

said second bracket being adapted to swing toward or away from said fixed bracket and both of said brackets being inclined downwardly and inwardly toward each other, electrodes loosely arranged in said brackets to gravitate to meet at their lower ends, a solenoid, a cam coöperating with said pivoted bracket for swinging the same toward or away from said fixed bracket, 10 means connecting said cam and said solenoid whereby the movements of said cam will be governed by the flow of electrical

current through said solenoid, and means governed by the movements of said pivoted bracket for holding said electrodes against 15 gravitation when said brackets are separated, substantially as described.

In testimony whereof I have signed my name to this specification in the presence of two subscribing witnesses.

GUSTAVE HUMBER.
